UNITED STATES PATENT OFFICE.

JAMES C. RAMSEY, JR., OF ANDOVER, MASSACHUSETTS, ASSIGNOR, BY MESNE ASSIGNMENTS, TO HERRICK AIKEN COMPANY, INCORPORATED, OF LAWRENCE, MASSACHUSETTS, A CORPORATION OF MASSACHUSETTS.

LAMP-SUPPORT.

1,093,009.

Specification of Letters Patent. Patented Apr. 14, 1914.

Application filed October 31, 1912. Serial No. 728,821.

To all whom it may concern:

Be it known that I, JAMES C. RAMSEY, Jr., a citizen of the United States, residing at Andover, in the county of Essex and State 5 of Massachusetts, have invented a new and useful Lamp-Support, of which the following is a specification.

This invention relates to a lamp supporting and operating device capable of general 10 use, but particularly adapted for use on automobiles and the like.

The principal objects of the invention are to provide a universally adjustable lamp support of an extremely simple and inexpensive construction, and one which can be manipulated by any person without difficulty and without danger of getting the parts out of order; to provide a device of this character capable of turning on a preferably horizontal axis through an entire circle, and to provide a construction in which in addition to this movement the lamp can have a practically unlimited motion about an axis at right angles to the axis which has 20 just been referred to so as to get a universal range of adjustment and permit the lamp to be turned to direct its rays in any desired direction.

The invention also involves the adjustability of the lamp about a third axis at right angles to one of the others, a system of electrical connections which are readily controlled from the handle by which the main adjusting movement is secured, and improvements in details of construction and combinations of parts as will appear hereinafter.

Reference is to be had to the accompanying drawings in which—

40 Figure 1 is a side elevation of a part of an automobile showing a preferred embodiment of this invention applied thereto; Fig. 2 is a similar view of the lamp and its carrying frame on enlarged scale with parts 45 in section to show interior construction; Fig. 3 is a sectional view on the line 3—3 of Fig. 2 looking in the direction of the arrow, and on enlarged scale; Fig. 4 is a sectional view on the line 4—4 of Fig. 2 looking 50 downward, also on enlarged scale; Fig. 5 is a view similar to Fig. 3 showing a

modification; Fig. 6 is a sectional view on the line 6—6 of Fig. 5; and Fig. 7 is a view similar to Fig. 2 of another modification showing it in central longitudinal section. 55

The invention is shown as applied to the dash of an automobile and that is the preferable way of mounting it. For this purpose the dash is provided with a support 8 mounted thereon and extending upwardly 60 therefrom. This support is provided with a horizontal end 9 constituting a pivot for the lamp carrying frame 10. This frame is provided with a socket for receiving the pivot 9 and with a screw 11 entering a circumferential slot 12 in the end of the pivot. At the end the frame is slotted at 13 and a collar 14 is secured by a set screw or in any desired way to clamp the frame to the support. The parts are lubricated by a wick or 70 the like saturated with oil and held in a slot in the frame by a plate 16.

On the central part of the frame is mounted a hollow handle 18 by which the frame is adapted to be turned on the pivot 9. This 75 handle is provided at the end with a hand-hold 19 which is fixed on a rod 20 passing through the hollow handle and through the frame. On its front end it is provided with a miter gear 21 meshing with a miter gear 80 22 fixed on the bottom of a member 23 which is pivoted by means of a screw 24 or the like to turn on an axis perpendicular to the pivot 9 and also to the handle. In the normal position of the parts this axis 85 is vertical. On this the member 23 turns when the hand-hold 19 is turned on its axis as will be obvious. This member 23 supports the lamp frame 25 and the latter is adjustable thereon about a horizontal axis, 90 and can be secured in adjusted positions by means of a screw 26.

The lamp is shown with an ordinary casting 27 and reflector 28, but it will be understood that any desired kind of lamp and fittings can be employed. An electric lamp 95 is shown provided with electrical connections 29, one terminal of which is connected with one of two wires 30 that extend along the handle. These two wires are designed 100 to be electrically connected and disconnected by a pair of buttons 31 operating in a well

known manner, so that the operator when manipulating the hand-hold 19 can control the current in a very simple way.

It will be seen that by turning the handle 5 about the horizontal axis 9, the whole frame with the lamp can be turned from the position shown in the drawings to a position at the bottom in which the lamp faces rearwardly and in fact it can be turned clear 10 around 360 degrees if desired. Thus, the range of the lamp in this way is unlimited. It will be seen also that on account of the gear construction used for turning the lamp on the axis which is normally vertical the 15 range of the lamp about this axis is also unlimited. In this way by having these two unlimited adjustments the lamp can be turned to any desired position so as to throw its rays in any desired direction. When 20 turned to any position about these axes the lamp will remain in position without tightening any fastening devices.

The adjustment of the lamp about the axis of the screw 26 is intended to be of a 25 more permanent nature, thus, the lamp is so set that when the handle is in the most convenient position for the operator the lamp will be throwing its rays directly forward either horizontally or at such slight inclination 30 as may be desired.

In Figs. 5 and 6 a form is shown in which the frame 12^a is of a different construction, and the rod 20^a terminates within the frame and has a bearing at the end thereof. In 35 this case the gears 21 and 22 are inclosed within the frame. The gear 22 is mounted on a shaft 23^a to which is fixed the lamp frame proper 25^a. In this case the same range of adjustments is possible.

40 In Fig. 7 is shown a form in which the frame or casing 12^b is mounted in the same or any equivalent way, and the rod 20^b is connected with a shaft 23^b by means of a knuckle joint 35 or the like. This accomplishes the same results as far as the two unlimited adjustments are concerned.

It will be seen that by the constructions shown and any modifications thereof within the scope of this invention, a very simple 50 arrangement is provided for securing an unlimited range for the lamp and yet it is of such a character that no complicated manipulation is required, and there are no parts that are likely to get out of order, or that 55 are cumbersome or ungainly in appearance. At the same time the manipulating handle is located in a convenient position.

Although I have illustrated and described 60 only three forms of the invention, I am aware of the fact that it can be carried out in many other forms, and with modifications in many of the other details without departing from the scope of the invention as expressed in the claims. Therefore, I do not 65 wish to be limited in these respects, but

What I do claim is:—

1. In a device of the character described, the combination of a support having a horizontal member projecting therefrom, a lamp carrying frame mounted to swing on said member as a pivot, said frame having a handle thereon and movable therewith for manipulating it, and a lamp mounted on and movable with said frame. 70

2. In a device of the character described, 75 the combination of a support having a pivot, a lamp carrying frame mounted to swing on said pivot, said frame having a handle thereon and movable therewith for manipulating it, a lamp mounted on and movable with 80 said frame, and means for turning said lamp on the frame about an axis transverse to the axis of the pivot.

3. In a device of the character described, 85 the combination of a support having a horizontal pivot, a lamp carrying frame mounted to turn about said pivot, said frame having a handle projecting therefrom and movable therewith for operating it, and means connected with and operated by the handle 90 for turning the lamp on an axis transverse to the handle.

4. In a device of the character described, 95 the combination of a frame, a lamp carried thereby and rotatable thereon, a handle extending from the frame, a hand-hold on the end of the handle rotatable thereon, a rod connected with said hand-hold extending through the handle, a bevel gear on the rod, and a bevel gear connected with the lamp 100 meshing with the first named bevel gear, whereby the rotation of the hand-hold will cause the lamp to be turned.

5. In a device of the character described, 105 the combination of a lamp carrying frame mounted to turn, said frame having a handle thereon for turning it on an axis transverse to the axis of the handle, a lamp mounted on said frame, and means connected with the handle for turning the lamp 110 on an axis transverse to the handle through an unlimited range, said lamp being adjustable through an arc about a third axis transverse to the handle and in a plane parallel to the first named axis. 115

6. In a device of the character described, 120 the combination of a frame adapted to turn about a horizontal axis, a lamp mounted thereon and adapted to turn on the frame on an axis transverse to said horizontal axis and also adjustable about a third axis transverse to the last named axis.

7. In a device of the character described, 125 the combination of a frame adapted to turn, a handle projecting from the frame for operating it, a rod extending through the handle, a hand-hold on the handle fixed to the rod, a lamp on the frame, means connected with the rod for turning the lamp on an axis transverse to the axis on which the 130

frame turns when the hand-hold is turned on the handle, and electrical connections extending through said handle to the hand-hold for controlling the operation of the lamp.

8. In a device of the character described, the combination of a support having a pivot, a lamp carrying frame mounted to turn about said pivot, said frame having a handle projecting therefrom and movable there-with for operating it, and means connected

with the handle for turning the lamp, said means being housed within the handle and frame.

In testimony whereof I have hereunto set my hand, in the presence of two subscribing witnesses.
